UNITED STATES PATENT OFFICE.

LOUIS ALBERT BECHT, OF PARIS, FRANCE, ASSIGNOR TO EDOUARD VIOLIER, OF SAME PLACE.

PERMUTATION-LOCK.

SPECIFICATION forming part of Letters Patent No. 399,002, dated March 5, 1889.

Application filed August 24, 1888. Serial No. 283,643. (No model.) Patented in France August 16, 1882, No. 150,654, and in Belgium August 19, 1882, No. 58,806.

To all whom it may concern:

Be it known that I, LOUIS ALBERT BECHT, a citizen of France, residing at Paris, in the Department of the Seine, have invented a new and useful Improvement in Safe-Locks, (for which I have obtained patents in France, No. 150,654, dated August 16, 1882, and Belgium, No. 58,806, dated August 19, 1882,) of which the following is a specification.

10 This invention relates to a new system of locks mainly designed for safes, but applicable to other purposes, and capable of use in various forms—such as padlocks, square-door-locks, and so on.

15 The part of my improved locks can be made by ordinary mechanical means—such as the lathe, the milling-machine, and the stamping press or punch. It is impossible to force them or to discover the secret of their

20 operation, which is a great advantage over the locks actually in use, whose combination of letters or figures can be ascertained by a persevering thief. In case a meddling or evil-disposed person should derange the position of the parts, it is easy to make the lock operate the same as if it had not been touched. By means of my system, therefore, I obtain complete security, while at the same time I effect a very great economy of manual

25 labor.

30 In the accompanying drawings, locks constructed in accordance with the invention are exhibited by way of example, the like letters indicating the same or corresponding parts in all figures.

35 Figure 1 is a perspective view, partly in section, of a round lock, the bolt and its controller or operating-cam being not shown. Fig. 2 is an axial section of another of same

40 general pattern, the bolts being not shown. Fig. 3 is a detail view in perspective of one of the parts. Fig. 4 is a plan, and Figs. 5 and 6 sections transverse to the axis of the lock shown in Fig. 2. Fig. 7 is an elevation,

45 partly in section, showing the bolt and operating-cam for the lock of Fig. 1, together with an arrangement for an additional snap-bolt for use when it is not desired to employ the lock proper. Fig. 8 is a plan of the lock

50 shown in Fig. 1, the bolt being omitted. Fig.

9 is an axial section, and Figs. 10 and 11 transverse sections, of the same, the bolt being shown in Figs. 9 and 11 but not in Fig. 10; and Figs. 12 and 13 are views in sections at right angles to each other of a square lock.

55 In each of the locks shown there are four screws for adjusting as many carriages; but the number of these can be varied, and it will be understood that what is said of locks with four carriages is to be applied (with such modification as may be necessary) to those with, say, five, six, ten, or as the case may be.

60 Referring to Figs. 1 to 11, A is the hollow cylindrical lock-case, which is suitably secured to the door of the safe by a flange or plate, *w*, at the front of the lock in Figs. 2 and 4, and at the back in Figs. 1, 8, 9, 10, and 11. In the case is nicely adjusted a cylinder, B, with cheeks *b b'*, with four holes, *c c'*, respectively, 65 in each, in which holes are journals *d d'* of the four screws *D' D² D³ D⁴*. Each of these screws can be turned by any suitable means—such as a key inserted in the hollow *d²* in the end of each of the screws and engaging a notch at the bottom of the hollow—and I may have a similar hollow, *d³*, in the opposite end, if I desire to manipulate the screws from both sides—as, for example, in a lock to be opened from either side.

70 Each screw engages a carriage or nut, *E' E² E³ E⁴*, respectively, of the form shown best in Fig. 1, there being on the outside two wings, *e e'*, with a groove between them in which fits loosely (or with only slight friction) a block, *F' F² F³ F⁴*, respectively, such as shown in perspective in Fig. 3, each block having on the outside a tongue which fits in a slot, *f' f² f³ f⁴*, respectively, and being held by a screw, *g' g² g³ g⁴*, respectively tapped into the block after being inserted through a spring, *G' G² G³ G⁴*, which bears upon the outside of the case A. These springs *G' G² G³ G⁴* hold the blocks *F' F² F³ F⁴* in place but permit them to be shifted along the slots *f' f² f³ f⁴* by the application of sufficient pressure. The blocks *F' F² F³ F⁴* are thus adjustably mounted on their support A.

75 If all the blocks fit between the wings *e e'* of the corresponding carriages *E' E² E³*

as shown in Figs. 1, 6, 11, it is possible to turn the cylinder B, together with its screw D' D² D³ D⁴ and carriages E' E² E³ E⁴, since the wings on said carriages will slide over the blocks, and this turning is utilized to control the lock-bolt or bolt-work of the safe by a suitable bolt-controller, such as hereinafter described, for example, or of any suitable description, the controlling being direct or indirect by an actuating or a dogging action. On the other hand, if the blocks F' F² F³ F⁴ are not between the wings e e', but occupy the position shown in Figs. 5 and 11, (the blocks occupying the spaces between the ends of the wings e e' on one carriage and the adjacent ends of the wings on the next carriage,) they will permit the cylinder B to turn, provided each block registers with the groove between the wings; but if they do not so register they will prevent the cylinder B from turning and will thus dog the cylinder B or obstruct its rotation.

When in the position shown in Figs. 5 and 11, each carriage can, by rotating its screw D' D², D³, or D⁴, be adjusted independently of its blocks F' F² F³ F⁴, which remain stationary on the case A, so as to bring said carriage into and out of position to register with its said block and thus cause the latter to act or not to act as an obstruction to turning the cylinder B. In the usual operation of the lock the blocks F' F² F³ F⁴ are set in different positions in their respective slots, so that the carriages E' E² E³ E⁴ will have to be adjusted to different positions to secure a proper registry. The relative positions of the blocks F' F² F³ F⁴ determine the combination or secret of the lock.

In opening the lock by a person familiar with the combination, he proceeds by turning the screws D' D² D³ D⁴, so as to run the carriage back against, say, the cheek b'. Then he gives to each screw so many turns or fractions of a turn as will make the carriage register with corresponding block. This he does readily, knowing the combination, or, in other words, knowing how many turns or fractions of a turn will be necessary; but if a person has not the information it will be almost or quite impossible to make all the carriages and blocks register.

To facilitate counting the turns of the screws D' D² D³ D⁴, springs R, Figs. 10 and 11, are arranged to bear against flat places t on the said screws, it being easy to notice whether or not the spring bears upon the flat place or a round portion of the screw.

The cylinder B, as shown in Figs. 7, 9, and 11, carries a bolt-controller in the form of a cam, C, which throws the bolt P back and forth by a quarter-turn, and, as shown in Figs. 2, 4, 5, and 6, it carries a bolt-controller in the form of a rotatory plate, I, with many arms, i' i² i³ i⁴, which are connected by ordinary or suitable connections with the bolt-work, (not shown,) so as to throw the bolt back and forth by a quarter-turn. When, therefore, a per-

son has brought the carriages E' E² E³ E⁴ into registry with the blocks F' F² F³ F⁴ in the position shown in Figs. 5 and 10, an eighth turn will bring each block between the wings e e' of the corresponding carriage, and another eighth turn in the same direction will complete the locking or unlocking and release the carriages from the blocks, so that the former can be adjusted independently of the latter by turning the screws. The person using the lock, therefore, after locking or unlocking, can adjust the carriages E' E² E³ E⁴, or as many of them as may be desired, so as to prevent any one not knowing the combination from turning the cylinder B.

To limit the angle through which the cylinder B can be turned, there is a pin, m, Figs. 2 and 4, on a spring, L, which takes into one or another of the holes the edge of the cheek b, according as the lock is opened or closed, or in the intermediate position shown in Figs. 6 and 10, one of these holes being represented at l, Fig. 2.

When it is desired to change the combination, the parts are brought into the position of Figs. 6 and 10, and then by turning one of the screws—say D'—the corresponding carriage, E', and block F' are moved to the end of the course—that is, till they are arrested by contact with, say, the cheek b'. Then the operator turns the screw D' in opposite direction, making, say, three, four, five, or more turns, as he may have determined, which will bring the block F' into a position represented by that number of turns. The block is moved with the carriage, because the pressure of the spring G' is not sufficient to prevent it from sliding on the case A. In like manner the other carriages and their blocks are run back and advanced again individually, the operator noting the number of turns or fractions of a turn in each case. He now, by an eighth of a turn, frees the carriages from the blocks and adjusts them lengthwise of the screws D' D² D³ D⁴ by turning the latter, so that they can only be restored by a person knowing how many turns were originally employed for each screw to fix the position of the respective blocks, F' F² F³ F⁴.

At the ends d' of the screws there are flanges h' h² h³ h⁴, which are interposed between the cheek b' and a washer, H. As shown in Fig. 9, the washer, and also the cam C, are fastened to the cylinder B by a screw, H'. This can be tightened so as to clamp the flanges h' h² h³ h⁴ with more or less pressure, so as to require the exertion of more or less strength in turning the screws D' D² D³ D⁴. As shown in Figs. 1, 8, 9, 10, and 11, the cylinder B is turned directly; but in the lock of Figs. 2, 4, 5, and 6 there is a spindle, K, to which the power is applied, and which communicates motion to the cylinder B by friction. The head of the spindle bears against the end of the cylinder B, and a nut, k², engaging the reduced and threaded extremity k' at the opposite end of the spindle, presses the rotatory plate I and

washer H against the flanges $h' h^2 h^3 h^4$ of the screws D' D² D³ D⁴ with yielding pressure, so that if the cylinder B is dogged or obstructed in its rotation an attempt to force it around 5 will simply turn the spindle K. At k is a projection to receive a key for turning the spindle K.

When it is necessary to open the safe often during the day—as, per example, at the hours 10 of payment—the combination-lock may be left open and the safe closed simply by a latch. In this case the bolt P, Fig. 7, is moved to the left, (or unlocked,) thus withdrawing the stud 1 from the notch 2 in the plate 3, so that the 15 latter can be turned by a handle, 4, on the outside of the door. By turning this plate 3 a pin, 5, thereon working in the slot 6 acts upon the latch 7 to release it and allow the door to be opened.

20 In Figs. 12 and 13 the case A' is square, and the carriages E' E² E³ E⁴, with their screws D' D² D³ D⁴, are supported on said case, while the blocks F' F² F³ F⁴ are mounted on the box 12, which is the equivalent of the cylinder 25 B, and which moves with the bolt, being shifted back and forth by the handle 8, which turns the bolt-controller in the form of a plate, 9, having an eccentrically-curved slot, 10, into which a pin, 11, in the box 12 projects. The 30 blocks F' F² F³ F⁴ are set in slots f' f² f³ f⁴, as before.

The carriages have the wings e e', which receive between the blocks F' F² F³ F⁴ or else act as obstructions to the movement of the 35 box 12, which carries the said blocks, and of the bolt g. The operation is substantially as before described with reference to Figs. 1 to 11. The spindle of the handle 8 is exposed on the opposite side of the locks, so as to receive 40 a key, and the screws D', &c., are adapted to receive a key at each end. It will be understood that the invention includes not only an arrangement in which the carriages are mounted on a movable carrier, as in Figs. 1 to 45 11, which controls the lock-bolt or bolt-work of a safe while the blocks are stationary, but also the reverse arrangement, as in Figs. 12 and 13, in which the blocks are mounted on the movable carrier and the carriages are supported by a stationary part; also, that the invention includes not only a rotary carrier, as in Figs. 1 to 11, but also a sliding carrier, as shown, for example, in Figs. 12 and 13; or a 50 movable carrier in general, and so also other modifications can be made without departing from the spirit of the invention.

The forms, dimensions, proportions, materials, and accessory devices may, of course, be varied at will.

60 I claim as my invention or discovery—

1. In a lock, the combination, with the bolt-controller, of the carriages and the blocks, one set movable with said bolt-controller, the other being stationary, and the screws which 65 adjust said carriages, so that motion of said controller is or is not dogged by contact be-

tween them and the said blocks, substantially as described.

2. The combination, with the bolt-controller, of the carriages and the blocks, one set movable with said bolt-controller, the other stationary, the screws which adjust said carriages, so that the said controller is or is not dogged, and the adjustable mounting for the 70 said blocks, so that their position can be altered to change the secret combination, substantially as described.

3. The combination, with the bolt-controller, of the carriages and blocks, one set movable with said bolt-controller, the other stationary, the screws which adjust said carriages, and the adjustable mounting for said blocks, composed of a friction-clamp and a slotted support, said blocks interlocking with 80 said carriages when in registering position, and said friction-clamps permitting them 85 when interlocked to be moved with said carriages by said screws, substantially as described.

4. The combination, with the bolt-controller, the carriages, and the blocks, of the screws which adjust the carriages, provided with flat places, and the springs which press upon said flat places, substantially as described.

5. The combination, with the bolt-controller, the carriages, and the blocks, of the screws which adjust the carriages, provided with flanges, and the washer held with yielding pressure against said flanges, substantially 95 100 as described.

6. The combination, with the bolt-controller, the carriages, and blocks, one set movable with the bolt-controller, the other set stationary, the carrier for said movable set and the screws which adjust said carriages, of the spindle having a friction-connection with said carrier, substantially as described.

7. The combination, with the bolt-controller, having an operating handle or device 110 on each side of the lock, the carriages, and the blocks, of the screws which adjust said carriages, having both ends accessible for operation on each side of the lock, substantially as described.

8. The combination, with the bolt-controller, of the carriages and blocks, the one set stationary and the other movable with said bolt-controller, the cylinder or its specified equivalent for carrying said movable set, 115 the case which supports the stationary set, and the screws journaled in bearings and adjusting the said carriages, substantially as described.

In testimony whereof I have signed this 125 specification in the presence of two subscribing witnesses.

LOUIS ALBERT BECHT.
